UNITED STATES PATENT OFFICE.

EARL V. SCHAAAL, OF DAYTON, OHIO.

METAL-POLISHING MACHINE.

Application filed November 27, 1922. Serial No. 603,547.

This invention relates in general to polishing machines and more particularly to a machine for polishing metallurgical specimens and the like which are thus prepared for microscopic study of their metallic structure.

It is the particular object of my invention to provide a polishing machine for rough polishing a plurality of specimens at a time, 10 providing for each novel resilient and adjustable holding means.

It is a further object of my invention to provide means whereby all of said holding means are so mounted as to be easily and 15 simultaneously brought into view for inspection. It is an object of my invention to provide a novel operating structure for polishing my specimens.

These and other objects will appear in the 20 accompanying specification and claims and will be disclosed in the accompanying drawings, in which:—

Fig. 1 is a plan view of my device.

Fig. 2 is a side elevation thereof.

25 Fig. 3 is a side elevation in detail of my holding and adjusting means.

Fig. 4 is a plan view of the device as shown in Fig. 3.

Referring with greater particularity to 30 the drawing, it will be seen that I have provided a polishing table 12 on which the polishing paper is to be placed. In carrying out my operation I first cement a piece of rough emery or sand paper to the table and 35 then place the finer polishing paper loosely upon that.

A yoke 20 is adapted to reciprocate to a limited degree longitudinally of the supporting frame being held in proper position by 40 guides 16, 17, 18 and 19 thereon. This yoke is adapted to be reciprocated by a crank 21 pivotally connected at 21^a to the yoke at one end and being pivotally connected at its other end to a crank disk 22. The crank 45 disk 22 is fixedly mounted on a shaft 22^a on which there is also mounted a relatively large worm gear 23 adapted to be driven by a worm 30 on a shaft 29 bearing in suitable bearings 32 and 33 which is in turn driven 50 by a motor 24 through the medium of pulleys 34 and 34^a and a belt 25.

A frame 11 is hingedly mounted on yoke 20 by means of hinges 14 and is adapted to be locked in operative position by a latch 15.

55 The polishing table 12 is dovetailed in a guide way on the frame 35, (see Fig. 4) and

adapted to reciprocate laterally of said frame as will be hereinafter described. In a depression in the frame 35 there is provided a bearing 27^a for a shaft 27^b upon 60 which there is fixedly mounted a relatively small worm gear 28 and a crank disk 27. The gear 28 is adapted to be driven by a worm 31 on shaft 29. A crank 26 is pivotally connected at 26^a to the crank disk 27 65 and at 26^b to the polishing table 12. Thus rotation of the shaft 29 will cause a reciprocating motion of the table 12 laterally of frame 35. Reference to Figs. 1 and 2 discloses in greater detail the specimen holders. 70

A pressure arm plate 9 is adjustably and pivotally mounted on frame 11 by means of a single screw 8. This plate has a portion adapted to act as a bearing for a pin shaft 10 on which a pressure arm 2 is pivotally 75 mounted and capable of motion in a vertical plane. A wing nut 1 is provided for adjusting the position of and hence the pressure of arm 2. A flexible resilient membrane 4, such as rubber or the like is stretched over 80 the rectangular opening in the end of pressure arm 2. A pair of clamp arms 5 of hard flexible steel wire are fixedly attached to base of the frame 11 by means of screws 6 and 7. These clamp arms have substantially right angularly shaped outer portions which cross each other so that the insertion of a specimen 3 spreads them apart, after the manner of a test tube holder, into, substantially, a parallelogram. The specimen 90 is thus held resiliently in its position in a horizontal plane by means of the clamps 5 and is held resiliently against the table 12 by the diaphragm or membrane 4 on the pressure arm 2, the degree of pressure of 95 the diaphragm being determined by the adjustment of the wing nut. A plurality of these specimen holders is provided.

The wire clamp 5 holding the specimen very close to the surface to be polished and 100 the diaphragm pressing down on top, tend to prevent rocking of the specimen; i. e. counteract any torque or turning movement caused by the relative movement of table and specimen.

105 From the foregoing my device will be seen to operate as follows: After the specimens 3 have had a flat surface ground upon them, they are resiliently and with an adjustable pressure, held in position against the table, 110 and resiliently held in any position in the horizontal plane to which they may have

been adjusted by set screw 8. The polishing table is moved laterally and rapidly back and forth across the under surface of the specimens while the frame 11 is slowly reciprocated above it in a direction at right angles to the motion of reciprocation of the table. When it is desired to inspect the specimens thus polished it is only necessary to unlatch the latch 15 and raise the frame 11 on its hinges to bring all the specimens into view simultaneously.

Specimens are reciprocated to prevent deep scoring of individual grains of abrasive travelling repeatedly in the same track. Rates of reciprocation must not be in relation of even multiples; that is to say, the reciprocations are not of such frequency that they will become synchronous at recurring intervals.

It is not intended that my invention shall be limited to the exact structure shown but only as defined in the following claims.

I claim:

1. In a device of the character described, a polishing table, a specimen holder including a pressure arm terminating in an open frame having provided stretched across and secured to an open frame with a flexible membrane to hold a specimen against said table, and means for operating said table.
2. In a device of the character described, a polishing table, a specimen holder including a pressure arm terminating in an open frame having provided stretched across and secured to an open frame with a flexible membrane to hold a specimen against said table, and means for operating said table, and means for adjusting the pressure of said membrane on said specimen.
3. In a device of the character described, a polishing table, a specimen holder comprising a flexible membrane for holding a specimen resiliently against said table, means for holding said specimen against lateral movement, and means for operating said table.
4. In combination, in a specimen holder, an open frame, a flexible membrane stretched across and secured to said frame for holding the specimen against a polishing table.
5. In combination, in a specimen holder, an open frame, a flexible membrane stretched across and secured to said frame

for resiliently restraining movement of said specimen in one direction and a resilient spring wire for holding the specimen.

6. In a device of the character described, a polishing table, a specimen holder comprising a flexible membrane for holding a specimen resiliently against said table and a pair of resilient spring wires for holding said specimen against lateral movement, and means for operating said table.

7. In combination in a specimen holder, an open frame, a resilient membrane stretched across and secured to said frame for holding the specimen against a polishing table and means for vertically adjusting the position of said frame.

8. In a device of the class described, a polishing table, a specimen holder comprising a flexible resilient membrane for holding a specimen against said table, means for holding said specimen against lateral movement, said means resiliently resisting vertical movement, and means for operating said table.

9. In a metallurgical specimen polishing machine, a supporting frame, a yoke adapted to reciprocate with respect to said frame, a polishing table adapted to reciprocate with respect to said frame, a strip of material having a very high coefficient of friction permanently attached to said table and a strip of abrasive material loosely applied upon the surface of said first mentioned strip.

10. In a polishing machine, in combination, a polishing table, a specimen holder, means for relatively moving said table and holder, means providing an extremely rough surface mounted on said table and a flexible strip of abrasive material resting loosely upon the said rough surface, whereby the said flexible strip is maintained in position upon said surface by friction alone.

11. In a polishing machine, in combination, a polishing table, a specimen holder, means for relatively moving said table and holder, a strip of rough abrasive paper permanently cemented to said table and a strip of polishing abrasive paper loosely applied to and held in place by said strip of rough abrasive paper.

In testimony whereof I affix my signature.

EARL V. SCHAAL.
